SPINNING FRAME

Robert Rulon-Miller, Bristol, R. I., and Warner H. Tabor, Uxbridge, Mass., assignors to Dixon Lubricating Sadle Co., a corporation of Rhode Island

Application February 5, 1953, Serial No. 335,228

11 Claims. (Cl. 19—136)

This invention relates to a spinning mechanism of the type used for spinning and roving frames.

By far the greater number of spinning frames in use at the present time utilize cap bars provided with slots in which the gudgeons of the top rolls rest. Some means is applied to the top rolls for urging the same toward the bottom rolls. The lint or fly which exists in the use of this sort of machines catches in these gudgeons, and it is difficult to keep the bearings clean.

Some attempts have been made to eliminate the cap bars and gudgeons and to weight and guide the top rolls through an arm extending above the top rolls, and this invention centers about an improvement in this type of guiding and weighting of the top rolls and the elimination of the cap bars.

One of the objects of this invention is to provide a unit assembly which may be used on frames already in operation.

Another object of this invention is to provide a unit assembly comprising an arm, top rolls, and the clearers for the top rolls, which unit may be either swung upwardly for ease in threading the frame or may be completely removed from the frame when desired.

Another object of the invention is to provide a weighting means comprising a stirrup through which weight is applied, which stirrup may be readily detached and attached to the arm of the assembly unit so that when it is desired that the assembly unit be swung upwardly or removed, the stirrup may be easily detached therefrom.

Another object of the invention is to provide the attachment or detachment of the stirrup to the unit assembly so that this attachment or detachment may be manipulated from the front of the frame such for instance as by a removable handle.

Another object of the invention is to support the stirrup in a position so that its attachment to the assembly unit carrying the top rolls may be easily had when such attachment is desired.

Another object of the invention is to utilize the stirrup for positioning the cradle which holds the intermediate rolls so that it may be maintained in a desired position when the assembly unit is swung upwardly or removed.

Another object of the invention is to provide an easy adjustment of the bearings through which weight is applied to the top rolls so that their position to accommodate varying distances of bottom rolls may be readily had.

Another object of the invention is to detachably hold the top rolls in assembled relation in the unit so that they may be easily removed as desired but will maintain their assembly with the unit unless intentionally removed therefrom.

Another object of the invention is to release the holding means for the top rolls from the top rolls so that this means will not friction on the top rolls when the top rolls are in working position in the frame.

Another object of the invention is to provide an assembly which will be low in height so that other parts in the

frame will not interfere with its being swung to raised position.

With these and other objects in view, the invention consists of certain novel features of construction as will be more fully described and particularly pointed out in the appended claims.

In the accompanying drawings:

Figure 1 is a sectional view through a spinning frame incorporating the invention and showing the top rolls weighted;

Figure 2 is a section on line 2—2 of Figure 1 but on a larger scale;

Figure 3 is a section on line 3—3 of Figure 1 also on a larger scale;

Figure 4 is a fragmental perspective view showing the means picking up the stirrup;

Figure 5 is a sectional view through the frame at a position different from that shown in Figure 1 but showing the stirrup as released from the arm and top roll unit assembly so that the top roll assembly may be swung upwardly into the position shown in Figure 9;

Figure 6 is an elevation of the stirrup shown by itself;

Figure 7 is a section on line 7—7 of Figure 5 showing the configuration of the slot through which the stirrup extends;

Figure 8 is an elevation looking at the two front rolls of the frame;

Figure 9 is a sectional view showing the top unit assembly as swung upwardly about a hinge on the supporting post upon which it is mounted;

Figure 10 is a perspective view of members mounted upon a threaded shaft with each member carrying a bearing for the top rolls of the frame, this part being a portion of the top roll assembly;

Figure 11 is a sectional view of a fragmental portion of the frame showing the stirrup as engaging trunnions on the crank arms of the top roll assembly.

With reference to the drawings, 10 designates the roll stand beam of the spinning frame which is usually of angle iron formation as shown in Figures 1, 5, and 9. Roll stands designated generally 11 are positioned at intervals along this rail and support the bottom front roll 12, the bottom back roll 13, and the intermediate assembly of top and bottom rolls designated as a unit 14 (Figure 9). The bottom rolls 12 and 13 extend from one roll stand to another and are provided at spaced locations along their length with a ribbed surface 15. Tandem lengths of bottom rolls are keyed together throughout the length of the frame and are driven from one end of the frame in a usual manner.

The top rolls which engage with the bottom rolls 12 and 13 each comprise an arbor 16 (Figure 8) which carries cots 17—17' at spaced intervals on the arbor.

The arbor is reduced as at 18 at a point between the cots providing shoulders 19 and 19'. In this case the arbor may extend beyond the cots, but as the extension which usually comprises gudgeons which are engaged by cap bars are not a part of this invention, it is immaterial whether the arbor extends beyond the end surface of the cots or not so far as the functioning of this invention is concerned.

The supporting posts are designated 25 and are located at intervals along the rear of the frame, being secured on the rod 26 extending lengthwise of the frame, which rod is held rigid with the frame, and the posts are held rigid with the rod by pin 26a while a screw 26' extends through the portion 76 into the bottom of the post.

An arm designated generally 20 (Figures 2 and 3) together with a front top roll and a back top roll, the clearers for these rolls, and the mounting means therefore constitute what we term a unit assembly. After detaching the stirrup from this unit assembly, it may be re-

moved bodily from the frame or it may be swung upwardly about a supporting post 25 which serves to mount and lock it in position.

This arm 20 is generally channel shape in cross section and comprises a top wall 21 and side walls 22 and 22' (Figure 3) depending therefrom, while there is an end wall 23 (Figure 1) at the front end of the arm.

The ear portions 27 and 27' (Figure 2) of the walls 22 and 22' at the rear end of the arm 20 are recessed to provide L-shaped slots 28 having legs 29 and 30 (Fig. 1). Each supporting post 25 is provided with a pin 31 which has its ends extending outwardly providing trunnions 32 and 32' to enter the slots 28. The arm has smooth parallel faces along these ear portions 27, 27' and the inner surface of its walls 22 and 22', while the post 25 is square and of substantially the same dimension as the distance between the inner surface of the arms. Thus, when the arm is positioned on the post 25 with its pin 31 in the slots, it will hold the arm in a plane at right angles to the axes of the bottom rolls while it may have a hinging action upwardly in this plane. It may be swung upwardly about the axis of the pin 31 while also sliding the pin from the portion 29 of the slot to the portion 30 of the slot so that the arm may be swung upwardly while the surfaces of the walls 22 and 22' will engage opposite parallel surfaces of the post 25 and guide the movement of the arm in its hinging action about the pin 31. Thus, the arm is held against rocking lengthwise of the rolls although it may swing toward and from the rolls.

In order to hold the arm in its upper position as shown in Figure 9, a pin 33 passes through the post 25 and protrudes outwardly beyond the arm to engage a notch 34 in the ears 27 of the arm 20 so as to latch therewith as shown in Figure 9 and hold the arm in raised position.

A unit sub-assembly carried by the arm is designated generally 35 and shown in perspective in Figure 10, which comprises a block 36 having a threaded hole 37 which may receive a screw 38 (see Figure 1) passing through a slot 39 in the arm and engaging the threaded opening 37 in the block 36 so as to adjustably mount it in the arm. This block carries a pin 40 at right angles to the screw hole 37 upon which there is pivotally mounted a threaded shaft 41. At one end of this shaft a bearing-carrying member 42 is threadedly mounted which may be adjusted as to position by further screwing the member 42 on the shaft. This member carries a synthetic resin bearing 43 which may be formed of some low-friction material and is held in position in the bearing member 42 by screws 44.

On the other side of the pivot of the shaft 41 there is a bearing-carrying member 45 which is also threaded on to the end of the shaft and which may be adjusted as to position by screwing the same at a different distance on to the shaft. This bearing-carrying member also has mounted in it a bearing 46 which may be of some non-metallic low-friction material also held by screw 44'. The members 42 and 45 may be relatively adjusted with reference to the block 36 by removing the block from the arm and threading these along the shaft at different distances thereon and then repositioning this sub-assembly in the arm. A spring 47 is mounted on a pin 48 secured to the arm and bears upon the arm and also upon the bearing member 42 as shown at 49 so as to tend to swing the shaft counter-clockwise, as seen in Figure 1, about its pivot 40. The shaft 41 is flat on opposite sides of the shaft at 41'. Each of these bearings has parallel ends and serves as guides to engage shoulders on the arbor of each top roll to hold the axis in desired position. This guiding is illustrated in Figure 8 where the ends of bearing 43 engage the shoulders 19, 19' to align the top roll while at the same time urging it toward the bottom roll when pressure is applied thereto.

The bearing member 45 has a pair of lips 50 and 51 extending downwardly from the member 45 (Figures 1

and 9) and which converge toward each other providing a narrow mouth 52 so as to retain the reduced portion 18 of the arbor of the back top roll in position. We have found it convenient, however, to provide the lip 50 rigid with the member 45 merely extending downwardly therefrom and against which the arbor may bear if necessary, while we have made the lip 51 in the form of a wire spring and secured it to the member 45 by a screw 53 which will permit of sufficient resiliency so that the arbor may be sprung into or out of the bearing as desired and yet will be held in a position spaced from the bearing when the assembly is lifted upwardly to lift the top rolls from the bottom rolls.

A member identical with the member 45 is designated 55 and is used for carrying a bearing 56 for engaging the arbor of the top front roll 57. The same lips are provided as heretofore described designated 50', 51'. This member 55 has its threaded opening mounted upon a screw 58 which is rotatably mounted in the front wall 23 of the arm and also has a bearing in the wall 59 which is carried by the opposite walls 22 and 22' of the arm. By rotating this screw 58 by means of its head 62 which is slotted, the position of the top front roll may be adjusted longitudinally with reference to the arm. By the adjustment of this roll and the back roll, the proper alignment with the bottom rolls may be obtained. The screw is circularly grooved at its end at 60 and held in position by spring ring 61 and its head 62 so that while it is rotatably mounted in the walls 23 and 59, it cannot be accidentally withdrawn therefrom.

Pressure is applied to the top roll through the arm by means of a stirrup designated generally 65 comprising a shank portion 66 which is bifurcated at its upper end providing arms 67 and 67' each with a hook 68 and 68'. The stirrup 65 has its shank formed in various sections. Thus, there is a section 111 which will rock freely through the elongated narrow slot 69, while at either side of this shaped section, the shank is twisted so as to provide section 112 to better support the arms 67, 67' and section 113 which supports the broadened portion 114 having therein slot 78. In order to be removed from the slot 69, the slot is enlarged as shown at 110, permitting twisting of the shank about its length. This stirrup passes through a slot 69 in the portion 70 of the frame and has a foot near the roll stand beam 10 designated 71 which is threadedly adjusted on to the end of the stirrup as at 72 so that the length of the stirrup may be varied to accommodate a change in the size of the rolls due to buffing. This foot is in close proximity to the rail 10 so that a small downward movement will permit it to rest upon the rail 10 as in Figure 5. A fulcrum 73 is adjustably mounted by means of threaded shank 74 and an opening 75 in the beam 10 to be engaged by the hook 76 of the lever 77 which passes through a slot 78 of the stirrup to engage the same as at 79 so that when a weight 80 is applied by hanging the same in a hook 81 of the lever, the stirrup will be urged downwardly.

The hooks 68 of the stirrup extend to a position in close proximity to shaft 82 (Figure 3) which extends through the opposite walls of the arm 20 and carries cranks 83, 83' which in turn carry trunnion pins 84, 84' extending outwardly therefrom, which pins serve as a catch means and are adapted to engage the hooks 68, 68'. Between the walls 22 and 22' and fixed to this shaft 82 there is a gear 85, and in order to turn this gear 85, we have provided a gear 86 which meshes therewith and which gear 86 is mounted on a shaft 87 which extends through the walls 59 and 23 to a location outwardly of the arm and is there provided with a head 88 of such shape that it may be readily engaged by a wrench or handle so that the shaft 87 may be turned to in turn rotate the shaft 82 through the gears 86 and 85 so that the pins 84, 84' (see also Figure 4) may be rotated from a position shown in full lines in Figure 11 upwardly and then downwardly to a location

shown in dotted lines at 89 (Figure 11) or as shown in Figure 9, which is in a position to disengage the pins from the hook, and when so disengaged from the hook, a spring 90 will force the stirrup rearwardly so that the hook will clear the pins 84, 84', allowing the arm to be swung upwardly to the position shown in Figure 4.

In order that the gears 85 and 86 may be properly aligned, we have mounted a sleeve 91 on the shaft 82 by reason of its ends abutting the wall 22' and the gear 85, will maintain the gear 85 in the desired position, while a similar sleeve 92 on the shaft 87 and located with its ends abutting the wall 59 and the gear 86 will maintain the gear 86 in its desired position. The gear 86 may abut at its forward end the bearing 91 to also assist in keeping it in position.

Pressure is applied to the arm 20, which by reason of the vertical slot 29 is free to move at its rear end vertically. The pressure is applied back of the location of the front rolls, and accordingly the arm will tend to pivot about the front roll so that there will also be pressure applied on the pivot 40 which carries the upper bearings which press upon the back rolls and intermediate rolls. Thus, there is a distribution of pressure as applied by the stirrup between the front, back, and intermediate rolls, and the arm 20 is free to move upwardly or downwardly by reason of the slot 29 at its back end, allowing free distribution of pressure on the rolls themselves. This movement also permits of pressure being applied regardless of the size of the rolls, which may vary due to buffering, which makes them smaller and occurs for truing them up after they have been in use.

The arm 20 also carries a pair of spring fingers 93 and 94 which are L-shaped in cross section and are held in position by a screw 95. These spring fingers are rolled over the outer ends, and one is longer than the other so that a shaft 96 of the front clearer roll 97 may be snapped into position with its surface engaging the top front roll, while a similar shaft 98 of the clearer roll 99 may be snapped into position between similar fingers for engaging the back top roll. By this arrangement the clearers as well as the back and front top rolls are mounted on the arm and will be moved upwardly when the arm is moved upwardly and will be moved from the frame when the unit assembly of the top rolls is removed from the frame.

The intermediate roll assembly is designated generally 14 and comprises a pair of end plates 100 connected by a platform 101 which plates are swivelly mounted upon an intermediate bottom roll 102 which extends through the frame similar to the bottom rolls 12 and 13. The plates 100, however, are spaced only slightly greater than each cot of the top roll and are notched at 106 so as to receive individual intermediate top rolls 103. A belt 107 extends about the intermediate top roll 103 and about a bar 108, while another belt 109 extends about the intermediate bottom roll 102 and a bar 109 providing contacting belts or aprons through which the yarn extends and is carried from the back rolls to the front rolls. This entire intermediate roll assembly will rock about the bottom roll 102 when no yarn is in the machine and the top roll assembly unit is lifted, but we prevent this action by providing on the stirrup 66 an arm 105 which will engage the platform 101 which extends between the plates 100, this arm engaging this platform 101 and holding the intermediate roll assembly from rocking about the roll 102 when the stirrup is in the lowered position as shown in Figure 5 so that its foot 71 engages the beam 10.

We claim:

1. In a spinning frame, a support, an arm movably mounted on said support and through which pressure is applied to the top rolls, catch means movably mounted on said arm at a location thereon spaced from said support and free thereof, a stirrup through which pressure is applied to said arm having attaching means at its upper end for engaging said catch means, and a rotatable shaft carried by said arm and operably connected to said catch

means for moving the same in and out of engagement with said attaching means.

5 2. In a spinning frame, an arm movably mounted and through which pressure is applied to the top rolls, a stirrup through which pressure is applied to said arm having spaced hooks at its upper end at a position to straddle said arm when the same is in the pressure applying position, trunnions movably carried by said arm for engaging said hooks, and manually operable means operably connected to said trunnions and operable for moving said trunnions in and out of engagement with said hooks.

10 3. In a spinning frame, a movable arm through which pressure is applied to the top rolls, a stirrup through which pressure is applied to said arm having spaced hooks at its upper end at a position to straddle said arm when the same is in the pressure applying position, trunnions movably carried by said arm for engaging said hooks, a rotatable shaft, and means connecting the shaft and 15 trunnions operable for moving the trunnions in and out of engagement with said hooks in response to rotary movement of the shaft.

20 4. In a spinning frame as in claim 2 wherein the trunnions are rotatable about a center spaced therefrom.

25 5. In a spinning frame having a roll stand beam, a movable arm through which pressure is applied to the top rolls, a stirrup through which pressure is applied to said arm having its lower end adjacent said beam and extending upwardly in the space between adjacent top rolls 30 and having attaching means at its upper end, an eccentrically mounted pin carried by said arm for engaging said attaching means to suspend said stirrup from said arm, and manually operable means for moving the said eccentrically mounted pin out of engagement with said attaching means, whereby said stirrup will drop into engagement with said beam and be supported thereon in position to be reengaged by said eccentrically mounted pin.

35 6. In a spinning frame, top rolls, an arm through which pressure is applied to the top rolls, a shaft pivoted intermediate its ends to said arm on its underside and bearings carried by said shaft adjacent its ends for engagement with said top rolls intermediate the ends thereof, and a spring bias on said shaft tending to move said shaft in one direction about its pivotal mounting.

40 7. In a spinning frame, top rolls, an arm through which pressure is applied to the top rolls, a shaft pivoted intermediate its ends to said arm on its under side, said shaft being threaded at its ends, bearing members threaded on the ends of said shaft, said members carrying bearings for engagement with said top rolls intermediate the ends thereof, and a spring bias on said shaft tending to move said shaft in one direction about its pivotal mounting.

45 8. In a spinning frame as in claim 6 wherein said spring bias comprises a spring acting between said arm and a part carried by said shaft.

50 9. In a spinning frame having bottom rolls and generally upright extending supporting posts at the rear of the bottom rolls located at intervals along the length of the frame, unit assemblies each comprising an arm and top rolls carried thereby, said arms each having side walls straddling said posts, and interengaging means carried by said posts and the said walls for detachably mounting a unit assembly on each post, and a stirrup for applying pressure to the top rolls detachably connected to each arm whereby upon detaching a stirrup from a unit assembly, that assembly may be lifted from the frame.

55 10. In a spinning frame having bottom rolls and generally upright extending supporting posts at the rear of the bottom rolls located at intervals along the length of the frame, unit assemblies each comprising an arm and top rolls carried thereby, said arms each having side walls straddling said posts and provided with an L-shaped slot
